CHARLES G. ASHLEY, OF CHICAGO, ILLINOIS, ASSIGNOR TO GENERAL ENGINEERING AND CONSTRUCTION COMPANY, LIMITED, OF TORONTO, CANADA, A CORPORATION OF ONTARIO.

PRINTING-TELEGRAPH SYSTEM.

1,164,907.

Specification of Letters Patent. Patented Dec. 21, 1915.

Application filed February 6, 1911, Serial No. 606,734. Renewed February 9, 1914. Serial No. 817,670.

To all whom it may concern:

Be it known that I, CHARLES G. ASHLEY, a citizen of the United States of America, and a resident of Chicago, county of Cook, 5 and State of Illinois, have invented a new and useful Improvement in Printing-Telegraph Systems, of which the following is a specification.

My invention embodies a novel improvement in automatic printing telegraph systems of the class using printed characters which from the nature of their making may be termed composite characters.

With regard to the method of producing the printed characters, printing telegraph systems may be divided broadly into two classes, those employing a plurality of printing type faces each type face representing a complete character and controlled electrically over the transmission line so as to be operated singly and successively to print on a recording surface, and those systems having a comparatively small number of printing types, each type representing one or 20 more component parts or elements of a completed character, the characters being formed by imprints, in proper relation from a plurality of the smaller number of component printing types representing the respective component parts of the complete characters.

My invention has as its principal object to greatly simplify the circuits and apparatus of systems of the latter class. This 35 I accomplish by reducing the number of receiving magnets to a minimum by an improved design of printing pen member, and by an arrangement of apparatus and system of operating circuits which enables me to 40 selectively imprint a plurality of type faces with a transmitter of minimum parts, employing a transmitting tape of a simplicity never before attempted in printing telegraph systems which record characters of the Roman 45 alphabet.

In the figures which accompany and form a part of this specification and in which like numerals designate corresponding parts throughout; Figure 1 illustrates in diagram 50 the apparatus and circuits at both a receiving and transmitting station and the conductors connecting them. Fig. 2 is a magnified view of the monogram or imprints of the printing type faces as they would appear

were all of the types imprinted upon a motionless recording surface. Fig. 3 shows a section of transmitting tape perforated to send the letters "A" and "J" by means of the transmitter illustrated in Fig. 1. Fig. 4 illustrates in diagram a preferred embodiment of my device and discloses the circuits and apparatus at both a receiving and transmitting station and the conductors connecting them. Fig. 5 shows a die plate or templet desirable for perforating the transmitting tape for use with the system disclosed in Fig. 4. Fig. 6 shows graphically the periodicity of the voltage of the current used to effect the selection of the imprint of the type faces of the device of Fig. 4 and is so placed with relation to Fig. 5 as to clearly disclose the time relationship existing between the magnet selection currents and the imprint selection currents. Fig. 7 illustrates a sectional transmitting tape perforated to form all of the characters necessary to transmit intelligence in the Roman alphabet with the device of Fig. 4. Fig. 8 illustrates in diagram the apparatus and circuits for the transmitting and recording of simultaneous messages with the device of Fig. 4. Fig. 9 illustrates in diagram the receiving circuits and apparatus of Fig. 8 showing an alternative method of supplying the recording current.

Describing first the receiving device and circuits in order that the requirements of the transmitting devices may be more fully understood, Fig. 1 shows in diagram at the left the receiving device which comprises a pair of electromagnets 20 and 22 polarized by means of the permanent magnets 10 and 12. The electromagnets 20 and 22 are so wound that when placed in series each to each and connected with one of the line conductors and ground, an impulse of current of one polarity over the line and ground will cause their cores to assume unlike polarities while an impulse of current over the line and ground in the opposite direction will cause a reversal of the previous polarity. The permanent magnets 10 and 12 when the electromagnets are deenergized, cause like poles on each of the free extremities of the electromagnets 20 and 22. The pole faces of the electromagnets 20 and 22 are provided with insulation as 20' and 22'. Armatures 1 and 2 are pivoted at one ex-

tremity and extend beyond the pole faces of the magnets 20 and 22 and are attracted thereby. Each armature comprises two metallic strips, each strip being insulated from its adjacent strip and from the balance of the device. Each strip bears upon its free extremity a printing type face as 1', 1³, 2² and 2⁴, the imprints of the faces being shown greatly enlarged in Fig. 2. The strips bearing printing types 1' and 2² are connected together and to one of the line conductors 35, while the strips bearing types 1³ and 2⁴ are likewise connected together and to the ground 32 through conductor 33.

15 A platinum coated or surfaced anvil 30 is placed adjacent to all of the printing types and may be adjusted in its distance therefrom by means of the screw 30'. A tape sensitized with any of the well known 20 chemical compounds for electrolytic printing, such as a mixture of nitrate of ammonium, chlorid of ammonium and red prussiate of potassium, rests on the surface of the anvil in a position to receive the impressions from any one of the printing type faces.

It will be noted that, if an impulse of predetermined polarity be sent over line conductor 34 and ground, one of the magnets 20 or 22 will be energized to annul its normal polarization, and its armature, bearing type faces as 1', 1³, will under the influence of the spring 15 be brought into contact with the recording surface or tape 31, and that, depending upon the polarity of the potential impressed on the pens 1' and 1³, either face may be selectively imprinted; for with an electrolyte such as that mentioned and with iron printing faces and a platinum anvil, only the type face which is at a positive potential with respect to the recording surface and anvil will be imprinted; thus by means of a transmitting device which will selectively operate either armature 1 or 2 and simultaneously selectively place positive potential with respect to the recording surface 31 on either of the pen faces borne by the operated armature, either of the four pen faces 1', 2², 1³ or 2⁴ 50 may be selectively imprinted on the recording surface 31 and a plurality of imprints may be made successively to form complete and legible characters. Such a transmitter is shown at the right of Fig. 1 in which a pair of direct current dynamos 23 and 24 or other sources of current have their terminals of opposite polarity connected together and to the ground 25, while the positive terminal of dynamo 23 is connected to 55 brushes 14² and 14⁴ and the negative terminal of dynamo 24 is connected to brushes 14' and 14³. A brush 13 is of sufficient width to bear upon both brushes 14' and 14² and make contact therewith while a brush 16 is of sufficient width to bear upon

both brushes 14³ and 14⁴ and make contact therewith. The brushes 13 and 16 are normally held out of contact with their adjacent pair of brushes by a transmitting tape 17. It will be noted that by the proper transverse spacing of a perforation in tape 17 with respect to the brushes 14³ and 14⁴, a positive or negative impulse of current may be sent over line conductor 34 and ground to operate selectively either armatures 1 or 2 and cause the pen faces borne thereby to make contact with the sensitized tape 31, and that by a proper transverse spacing of the perforations in the tape 17 with respect to brushes 14' and 14² the potential of the pen face with respect to the sensitized tape 31 and anvil 30, may over conductor 35 and ground be changed at will. Hence by a predetermined spacing in the tape 17 of these two sets of perforations above noted, either armatures 1 or 2 may be selectively operated and either of the pen faces which they bear may be given a positive potential with respect to the sensitized tape 31 to cause the recording upon the tape 31 of a particular type face.

Referring now to Fig. 2 which shows an enlarged view of the pen faces as they would appear were all simultaneously imprinted on a recording surface, pens 1', 2² and 1³ are each in width equal to the width of a complete normal character such as "H." The width of a complete normal character is divided into eight arbitrary units, each pen being separated from its fellow by one of these arbitrary units. Pens 1' and 1³ are carried by armature 1 Fig. 1, while pens 2² and 2⁴ are carried by armature 2.

Referring to Fig. 3 which shows a section of transmitting tape perforated to send the letters A and J by means of the device of Fig. 1, longitudinal lines 15', 15², 15³ and 15⁴ correspond to the line of contact of the brushes 14', 14², 14³ and 14⁴ respectively with the brushes 13 and 16. Transverse lines 4^a, 2^a and 1^a, etc. are placed a distance apart equal to the unit of width of the pen faces 1', 2² and 1³. Thus, in order to select either pair of pen faces 1' and 1³ or 2² and 2⁴, it is only necessary to place a perforation along line 15³ or 15⁴, and to select the particular pen face of a pair as 1' and 1³; it is necessary to place a perforation opposite the perforation in the line 15³ or 15⁴ but along the line 15' or 15². Conceive now the tape 17 to move in a direction as indicated by the arrow of Fig. 3 between the brushes 13, 16 and 14', 14², 14³ and 14⁴ of Fig. 1 at a speed which allows one transverse spacing of the tape 17 to pass through the brushes while a corresponding interval in the recording tape 31 is passing from right to left under the pen faces as viewed in Fig. 2. The letter "A" may now be recorded as follows: The tape 17 passes through the brushes of 130

the transmitter until the perforations along the line 4^a permit contact between the brushes 14^a and 16 and brushes 14' and 13, thereby sending a positive impulse over line 5 conductor 34 through magnets 22 and 20 and ground and causing armature 2 bearing type faces 2² and 2⁴ to be released from the influence of polarizing magnet 12 and under the influence of spring 2⁵ bring its pen faces 10 into contact with the receiving tape 31 and simultaneously with this impulse, an impulse of negative polarity is sent which traverses ground, pen face 2⁴, recording tape 31, anvil 30, again tape 31, pen face 2², line conductor 15 35 and is grounded through the transmitter. This causes pen face 2⁴ to become positive with respect to the recording surface 31 and hence causes its imprint thereon, but not causing the imprint of pen face 2². Then 20 after a time interval of eight units, pen 2⁴ is again printed as above indicated and after two time intervals, pen 2² is printed by sending through conductor 34 a positive impulse and reversing the direction of the current 25 flow through pen faces 2² and 2⁴ which causes pen face 2² to become positive with respect to the recording surface 31, thus imprinting pen 2² and not pen 2⁴ and again after one time interval sending a negative 30 impulse through conductor 34 which causes the operation of armature 1 to bring its pen faces 1' and 1³ into contact with the recording surface 31 and sending a positive impulse along line conductor 35 through pen 35 1', anvil 30, pen 1³, and ground, which as pen face 1' is therefore positive with respect to the recording surface 31, pen 1' is imprinted and not pen 1³. Similarly the letter J may be recorded as may all the characters 40 of the Roman alphabet as will be subsequently more clearly disclosed.

Referring to Fig. 4 in which I have shown a preferred embodiment of my invention, the receiving device and its circuits are 45 the same as that of Fig. 1; the transmitting device and circuits shown at the right differ however greatly from that of Fig. 1 and comprise a shaft 13 upon which is rigidly mounted a metallic drum 14 bearing a 50 median row of equally spaced insulating, invaginating projections 14⁵. A brush 11 is rigidly mounted upon the frame of the transmitter and makes contact with the drum 14 upon either side of the row of projections 55 14⁵. Brush 11 is connected to line connector 34 and through the electromagnets 22 and 20 of the receiving device to ground 32. A pair of wipers 15 and 16' are rigidly attached, parallel to each other, to a 60 shaft 13' and are insulated therefrom. Shaft 13' and shaft 13² are geared together so that while shaft 13' is rotating through one complete revolution, shaft 13² is rotated through an angle which is defined by the 65 distance between any two projections as 14⁵ on drum 14.

A pair of annular commutators 27 and 18 are rigidly attached to the frame of the transmitter and are so placed as to encircle wipers 15 and 16' respectively, to permit these wipers to make contact between the segments of their respective commutators. Commutator 27 is divided into one substantially semicircular segment and two substantially quarter-circular segments, the semicircular segment being connected 75 through conductor 35 with the armatures 1 and 2 of the receiving device and through them with ground 32. One of the quarter-circular segments of commutator 27 is connected to the negative terminal of dynamo 80 23 while the remaining quarter-circular segment is connected to the positive terminal of dynamo 24; the remaining terminals of dynamos 23 and 24 are connected together and to ground 25. Commutator 18 comprises one substantially semicircular segment and four substantially eighth-circular segments, the semi-circular segment being connected through conductor 19 with the journal of the shaft 13² and thence to the 85 metallic drum 14. A constant relation is at all times maintained between the positions of each wiper 15 and 16' with respect to the segments of their respective commutators 27 and 18 and the position of the projections 90 14⁵ of the drum 14 with relation to the contact line of the brush 11 on the drum 14. This relation is such that as the drum 14 rotates a distance equal to that defined between any two projections thus carrying the 95 contact line of the brush 11 with the drum 14 through the same distance, the wiper 15 makes one complete revolution, thereby placing two negative impulses and two positive impulses on conductor 35 and ground. 100 Simultaneously wiper 16' is making one revolution, thereby placing four negative impulses and four positive impulses on conductor 34 and ground. In effect this places an alternating current of a definite periodicity on conductor 34 through electromagnets 22 and 20 to ground while an alternating current of one half the periodicity of that placed on the electromagnets 22 and 20 is placed on conductor 35 through the pen 110 faces 1', 1³, and 2², 2⁴ to ground. The relation of the rotation of the wipers 15 and 16' with relation to the contact line of brush 11 with drum 14 and the projections 14⁵ being such that a positive potential is always 115 impressed on the drum 14 by means of commutator 18, and a negative potential is impressed on the line 35 by means of the commutator 27, while the contact line of brush 11 is passing any projection as 14⁵ on 120 drum 14.

Referring to Figs. 5 and 6 which show respectively a templet for perforating the tape to send all the impulses necessary to record all the characters in the Roman al- 130

phabet with the device of Fig. 4, and the periodicity of the current impressed upon the pen faces by means of commutators 27 and wiper 15. The perforations as 4°, 3°, 2°, 5 and 1° are placed along a line 11' and are spaced longitudinally by equal units which correspond to the unit of width of the pen faces 1', 2', and 1° of Fig. 2. A row of perforations as 14° Fig. 5 are spaced a distance 10 apart equal to eight of these units of tape distance and are adapted to engage the projections 14° of the drum 14. Thus as there are eight tape divisions between any two perforations as 14° and as the wipers 15 and 15 16' rotate with such relation to the drum 14 as to make a complete revolution each while the drum is rotating the distance defined by that between any two perforations as 14°, it follows that four sets of positive and negative impulses may be sent through eight 20 perforations along the line 11' of Fig. 5, while the potential of the pen faces as 1', 1°, with respect to the anvil 30 and receiving tape 31 may be changed twice. Thus a positive 25 and a negative impulse may be sent over conductor 34 through magnets 22 and 20 to ground to operate armatures 1 and 2, while a negative impulse is impressed on one of each pair of pen faces borne by armatures 2 and 1 to cause the printing of that 30 pen of each pair which is at a positive potential with respect to anvil 30 and again, a positive and negative impulse may be sent over conductor 34 through electromagnets 35 22 and 20 and ground to cause the operation of armatures 2 and 1, while a positive impulse is impressed on one of each pair of pen faces borne by armatures 2 and 1 to cause the printing of the remaining one of 40 each pair of pen faces, thus any one of the four pen faces as 1', 1°, 2' and 2° may be selectively imprinted by means of a single row of contact perforations in tape 26' when provided with a row of registry perforations 45 and passed between drum 14 and brush 11. By properly spacing the perforations along the line 11' as shown in the templet Fig. 5 and passing the transmitting tape 26' so perforated through the transmitter and a 50 recording tape 31 through the receiver at a speed corresponding to the transmission tape, all the characters of the Roman alphabet may be recorded on the receiving tape 31. A tape which may be conceived to have 55 been perforated through the use of the templet Fig. 5 is shown in Fig. 7 and illustrates the various spacings and groupings of perforations along the line 11' and their relation to the registry perforation along line 60 14°, to effect the recording of all of the characters of the Roman alphabet.

The manner of forming legible characters by the use of this tape is as follows:—Assuming that the transmission tape 26' is 65 being drawn between the drum 14 and brush

11 from right to left as viewed in Fig. 7 with its registry holes as 14° engaging the projections 14° of drum 14 and that the receiving tape 31 is being drawn at the same or a proportional lineal rate from right to left 70 between the anvil 30 and the symbol formed by the pen faces 1', 1°, 2' and 2° of the receiving device Fig. 4 as viewed in Fig. 2. Any two consecutive perforations in the tape are spaced a distance apart equal to one-eighth the distance between any two registry perforations, there being thus eight tape units between any two registry perforations and these tape units of the transmitting tape corresponding on the receiving tape to one-eighth the width of the pen faces 1', 2' and 1° 75 through the proper speed relation of the two tapes. Then in recording the letter "A" the first perforation 4° which is spaced on the same transverse line with the registry perforation in the transmitting tape 26' allows contact to be made between line conductor 34 and the positive terminal of dynamo 24 through drum 14 and commutator 18 and thus places a positive impulse of current 80 through the electromagnets 22 and 20 and thereby annuls the normal polarization of magnet 22 and causes armature 2 to bring its pen faces 2' and 2° into contact with the receiving surface 31, and as commutator 85 27 is in a position which allows of a negative potential to be impressed upon pen faces 2' and 2°, it follows that when the two pen faces are in contact with the sensitized tape 31, that a current will flow from ground 100 32 through pen face 2° through sensitized tape 31 to pen face 2' and thence through line conductor 35 and commutator 27 to the negative terminal of dynamo 23, thereby causing pen face 2° to be positive with respect to the sensitized tape 31 and thence causing its imprint and not the imprint of pen 2'. After the tape 26' has moved eight tape units, the contact line of brush 11 with drum 14 will again be opposite a projection as 14° 110 and each wiper 15 and 16' of commutators 27 and 18 will have made one revolution, which will allow of a positive impulse being sent through a perforation in the tape 26' at that instant along conductor 34 through 115 electromagnets 22 and 20 to again actuate armature 2 to bring its pen faces into contact with the receiving tape 31. A negative impulse of current will be impressed upon the pen faces which causes when they are 120 in contact with the receiving tape 31, a current to flow as before from ground to pen face 2°, sensitized tape 31 and thence through pen face 2', line conductor 35, commutator 27, to negative terminal of dynamo 23 thus 125 again imprinting pen face 2° a distance away from its previous imprint on the receiving tape of eight tape intervals. After a lapse of two tape intervals a perforation in the tape as 2° will, as wiper 16' has since the 130

previous impulse made one fourth of a revolution, allow a positive impulse of current to flow through conductor 34 through magnets 22 and 20 again actuating magnet 22 to release its armature 2 to bring its pen faces into contact with sensitized tape 31 and as wiper 15 has since the previous imprint made one fourth of a revolution a positive potential is impressed on the pen faces 2² and 2⁴ which, when they are in contact with the receiving surface 31, causes a current to flow from the positive terminal of dynamo 24 through commutator 27 line conductor 35 through pen face 2², receiving tape 31 to pen face 2⁴ and thence to ground, thus imprinting pen faces 2² and not 2⁴. This imprint will abut at its extremities with the previous imprints of pen 2⁴. Again after a lapse of one tape interval a perforation in the tape as 1°, will, as each wiper 15 and 16' has made substantially a one eighth revolution since the previous imprint, allow a negative impulse being sent over line conductor 34 through electromagnets 22 and 20 which will annul the normal polarization of magnet 20 and allow its armature 1 to bring its pen faces under the influence of spring 1⁵ into contact with the receiving surface 31, and simultaneously with such contact as a positive potential is impressed on the pen faces through commutator 27 over conductor 35, a current will flow from the positive terminal of dynamo 24 through commutator 27 and line conductor 35 through pen face 1' tape 31 to pen face 1³ thence to ground 32, thus causing the imprinting of pen face 1', the vertical leg of which coincides with a portion of the first imprint of pen 2⁴, while its horizontal portion will abut the last imprint of pen 2⁴ to form the letter "A." In a similar manner all the characters of the Roman alphabet may be recorded by the use of a tape perforated as shown in Fig. 7. It will be readily noted that while the system disclosed in Fig. 4 is cyclic in its operation, that of Fig. 1 is not, the armature actuating potential and the printing potential being selective arbitrarily by the transverse spacings of the perforations in the tape 17, Fig. 3.

It will be noted that all the characters of the English alphabet may be recorded by the use of the device of Fig. 1 by spacing the perforations as in the tape of Fig. 7, the potential of the magnet actuating current and printing current being determined by spacing the perforations along the lines 15³, 15⁴, or 15¹, 15² respectively.

Fig. 8 illustrates in diagram a device for sending simultaneous messages with the system disclosed in Fig. 4 and in view of the foregoing is largely self-explanatory. The armature actuating magnets 20, 22 and 60, 62 are connected in series each to each and placed in connection with the ground and

conductors 34 and 34' respectively. Conductor 34 is connected to brush 81 while conductor 34' is connected to brush 11. Brush 81 bears upon a metallic drum 84 such as that of Fig. 4, while brush 11 bears upon a similar drum 14. Pen faces 1', 41', 2², and 42² are connected together and to line conductor 35, while pen faces 1³, 41³, 2⁴ and 42⁴ are connected together and to ground 32 through conductor 33. Conductor 35 is connected to commutator 27. Commutator 18 is connected to the journal of shaft 13², while dynamos 23 and 24 are connected to commutators 27 and 18 as indicated. Shaft 13' bears wipers 15 and 16' and is geared to shaft 13² as indicated so that a ratio speed is maintained as that hereinbefore described. Thus it will be seen that the potential of the pen faces of each receiver is varied over the cyclic wire 35 while a pair of transmitting tapes perforated as in Fig. 7 may be placed on drums 14 and 84 and record their messages on the receiving tapes 71 and 31 respectively.

An alternative method of supplying the imprinting currents to the pen faces is shown in diagram in Fig. 9 in which the connections are similar to that of Fig. 8 with the exception that the cyclic wire 35 of commutator 27 is connected through the winding of a polarized relay 65 with ground 32, while the pen faces 1', 41', 2² and 42² are connected together and through conductor 68 with the positive terminal of battery 63 and the negative terminal of battery 64 while pen faces 1³, 41³, 2⁴ and 42⁴ are connected together and through conductor 67 to the armature of the polarized relay 65. One contact 65' of relay 65 is connected with the negative terminal of battery 63, while the other contact 65² is connected to the positive terminal of battery 64. Relay 63 is so polarized that when a negative impulse of current is placed through its coils by means of commutator 27, conductor 35 and ground, its armature will make contact with contact 65², thus placing a negative potential from battery 64 through conductor 68 on pens 1', 41', 2² and 42² and positive potential on pen faces 1³, 41³, 2⁴ and 42⁴ with respect to the sensitized tapes 31 and 71, and when a positive impulse of current is placed through the relay 65, the relay will make contact with contact 65', thus placing positive potential on pen faces 1', 41', 2² and 42² and negative potential on pen faces 1³, 41³, 2⁴ and 42⁴ with respect to the tapes 31 and 71. This accomplishes by local battery the selective imprinting of any particular pen face as before described.

This method has the advantage that the imprinting currents are always of a definite value independent of the length or electrical condition of the transmission line.

It is obvious from the foregoing that a

pair of alternating current generators may be substituted for the commutators 27 and 18, the one substituted for commutator 27 having one half the frequency of the one taking the place of commutator 18, and eliminate the use of the direct current sources 23 and 24, thus reducing the transmission mechanism to a minimum of parts of extreme simplicity. It is further obvious in order that the transmission tape shall not become too fragile because of the large number of substantially adjoining perforations which may occur in any particular grouping of perforations along the single line 11' that the perforations may be spaced with the same longitudinal spacing in two rows one either side of the central row of registry perforations and thus minimize the fragility of the perforated tape and increase its wearing qualities during transmission.

While I have illustrated only a few embodiments of my device, it is to be clearly understood that I may make numerous changes in the details of either without departing from the spirit or narrowing the scope of my invention.

Having thus described my invention, what I claim as new and desire to secure by United States Letters Patent, is as follows:

1. In a system of printing telegraphy, a plurality of printing elements, a receiving surface adjacent thereto, means for bringing said elements in predetermined groups into contact with said receiving surface and means for causing any element of a group in contact with said receiving surface to record its imprint thereon.
2. In a printing telegraph system, a receiver, a transmitter and conductors connecting them, said receiver comprising a receiving surface and a plurality of groups of printing elements, means for placing in a condition of potential operation a group of said printing elements and further means for selectively printing on said receiving surface any one of said elements of said group.
3. In a printing telegraph system, a receiver, a transmitter and conductors connecting them, said receiver comprising a receiving surface and a plurality of printing elements, means operable over said conductors whereby a particular group of said printing elements may be caused to make contact with said receiving surface and further means operable over said conductors whereby any one of said elements of said group may be recorded on said surface.
4. In a printing telegraph system, a receiver, a transmitter and conductors connecting them, said receiver comprising a receiving surface and a plurality of groups of printing elements, the elements of each

group being simultaneously operable over said conductors to make contact with said receiving surface and further means operable over said conductors whereby any one of said elements of said group of elements may be recorded on said receiving surface.

5. In a system of printing telegraphy, a receiving station, a transmitting station and conductors connecting them, means at said transmitting station for impressing upon said conductors two independent currents of variant periodicity, a plurality of printing elements at said receiving station and means at said receiving station for utilizing one of said currents to effect the selection of a group of said printing elements and further means for utilizing the other of said currents to effect the imprinting on a recording surface of any one of the elements of said group.

6. In a system of printing telegraphy, a receiver, a transmitter and conductors connecting them, said receiver comprising a pair of electro-magnetically operated armatures and a receiving surface, each of said armatures bearing a plurality of printing elements, means embodied in said transmitter for impressing on said conductors current impulses for selectively operating said armatures and further means embodied in said transmitter for impressing on said conductors current impulses for selectively printing on said receiving surface any one of said printing elements.

7. In a system of printing telegraphy, a receiver, a transmitter and conductors connecting them, said receiver comprising a pair of electro-magnetically operated armatures and a receiving surface, each of said armatures bearing a plurality of printing elements, said transmitter comprising means for impressing current impulses of variant polarity on said conductors to effect the selective operation of said armatures and means for impressing a potential of variant polarity upon said printing elements to effect the imprinting of any element on said receiving surface.

8. In a system of printing telegraphy, a plurality of electro-magnetically operated armatures, a plurality of printing elements upon each of said armatures, a recording surface adjacent to said printing elements, means for selectively operating said armatures to cause said printing elements borne thereby to make contact with said recording surface and means for selectively imprinting any one of said elements on said surface from a group borne by a selected armature.

9. In a printing telegraph system, a receiver, a transmitter and a pair of conductors and ground connecting them, said receiver comprising a receiving surface, a pair of actuating electromagnets, a pair of armatures controlled by said electromagnets, a

pair of printing elements borne by each of said armatures and insulated each from each, means operable over one of said conductors and ground whereby a particular 5 pair of said elements may be caused to make contact with said receiving surface and further means operable over the other of said conductors and ground whereby either of said elements in contact with said receiving 10 surface may be recorded thereon.

10. In a printing telegraph system, two line wires, four pen members, an electrolytic record sheet, magnets for operating said pen members to strike the record sheet in 15 pairs, a circuit over one of said line wires to select and move either pair of pen members into contact with the record sheet, and a circuit over the other line wire to polarize properly only one pen member of the selected 20 pair.

11. In a printing telegraph system, a plurality of line conductors, electrolytic recording sheets, a plurality of printing pens operative over said line conductors to strike 25 said recording sheets in pairs, and an electrolytic circuit operated over one of said line conductors to polarize operatively only one of the pens of each pair.

12. In a printing telegraph system, two 30 line circuits, four printing pens, an electrolytic sheet, means operative over one of said line circuits to cause two of said pens to make contact with said sheet, and means operative over the other of said line circuits 35 to polarize selectively only one of the said two pens.

13. In a printing telegraph system, a transmitter, a receiver, a line connecting them, said receiver comprising an electrolytic 40 recording sheet and printing pen members adjacent thereto, said members classified into pairs, means in the transmitter for rendering the pen members of a pair alternately potentially operative to record electrolytically upon said sheet, and means in 45 said transmitter for causing any pair of pens to strike said sheet.

14. In a printing telegraph system, a plurality of transmitters, a plurality of receivers, conductors connecting each a transmitter to a receiver, said receivers each comprising an electrolytic recording sheet and printing pen members adjacent thereto, said members classified into pairs, means associated 55 with the transmitters for rendering the pen members of all of the pairs alternately potentially operative to record electrolytically upon the recording sheet, and means for causing any pair of pens to make contact with the recording sheet.

15. In a printing telegraph system, a plurality of intelligence-transmission conductors, a transmitter at the sending end of each of said conductors, a receiver at the receiving end of each of said conductors,

each of said receivers adapted to operate by co-operation of magnetic and electrically polarized parts comprised in each receiver, means in and associated with the said transmitters for controlling the electromagnetically operated parts of their respective receivers over their respective line conductors for intelligence transmission, and an additional line conductor common to all of said receivers and controlling the electrical 75 polarization of the parts comprised in all of said receivers, said control being governed by means at the transmitting station directly connected to said additional line conductor and associated with said plurality 80 of transmitters.

16. In a printing telegraph system, a plurality of receivers, each containing movable and polarizable printing pens, line wires individual to said receivers and connected 85 to parts in said receivers controlling movement of said pens, and an auxiliary line wire common to all said receivers and connected to parts in said receivers controlling the polarization of said pens, a plurality of 90 transmitters transmitting to said individual line wires impulses controlling the movement of said pens, and a device auxiliary to said transmitters and transmitting over said auxiliary line wire electric currents for the 95 control of the polarization of said pens.

17. In a printing telegraph system, a plurality of receivers, each containing movable and polarizable printing pens, line wires individual to said receivers and connected to 100 parts in said receivers controlling movement of said pens, and an auxiliary line wire common to all said receivers and connected to parts in said receivers controlling the polarization of said pens, a plurality of transmitters transmitting to said individual line wires impulses controlling the movement of 105 said pens, and a device auxiliary to said transmitters and transmitting over said auxiliary line wire electric currents for the control of the polarization of said pens, each receiver with its connected line conductors and transmitter being operable independently of any other receiver for transmitting intelligence independently.

18. A monogram composed of four printing characters representing elemental lines by the combinations of which the letters of a recognized alphabet are constructed, a division of the monogram into units by 120 which all printing characters and their composites are measured, and a moving surface upon which the characters are printed, in combination with an alternating current having its alternations corresponding to the units of division and the rate at which the surface is moved, means by which the alternating impulses of the current cause the characters to be printed upon the moving surface, and means for intercepting a portion 125

tion of the alternating impulses so that the remaining impulses will cause the characters to be printed selectively.

19. A monogram composed of four type characters and divided into units, the characters representing elemental lines of a Roman alphabet, magnets for operating the characters separately, a moving receiving sheet, a source of alternating impulses for operating the magnets, the alternations being timed to each correspond to a movement of one unit of the receiving sheet, and means for intercepting all but selected ones of such impulses.

15 20. The combination with a plurality of sending devices at a sending station, and an equal plurality of receiving devices at a receiving station, of means for sending an equal plurality of messages and printing the same in Roman characters at the receiving station by sending electrical impulses over an equal plurality of wires plus one.

25 21. A source of alternating current, a plurality of wires over which the impulses of such current may flow, four printing characters associated with each wire and brought into printing condition by such impulses, a second source of alternating current having one-half the periodicity of the first source, a single line over which the impulses from the second source may flow, said single line being associated with all of the printing characters, and means for controlling the impulses flowing from both sources to

print in Roman characters as many simultaneous messages as there are wires from the first named source of current.

35 22. The combination with a plurality of type faces, a receiving surface, and electrically operated means for printing the type upon the surface, of an alternating current conveyed continuously to one part of the electrically operated means, a second alternating current potentially capable of being conveyed continuously to another part of the electrically operated means, and means for intercepting part of the impulses of the second current, the two currents coöperating to selectively print the type upon the surface.

40 45 23. A plurality of groups of printing pens, mechanically operating means for selecting groups and chemically operating means for causing a print to be made by any desired pen in the selected group.

50 55 24. A plurality of groups of printing pens, electrically controlled means for selecting groups of pens and chemically operating means for causing a print to be made by any desired pen in the selected group.

60 Signed by me at Toronto, county of York, and Province of Ontario, in the presence of two witnesses.

CHARLES G. ASHLEY.

Witnesses:

W. M. J. HERDMAN,
D. S. TOVELL.
